United States Patent Office

Des. 186,648
Patented Nov. 10, 1959

186,648

PILE FABRIC

Frank Hinett, Jr., Philadelphia, Pa., assignor to Artloom
Industries, Inc., Philadelphia, Pa., a corporation of Pennsylvania

Application June 3, 1959, Serial No. 56,192

Term of patent 14 years

(Cl. D92—1)

FIG. 1 -

FIG. 2 -

Fig. 1 of the drawings is a fragmentary plan view of a pile fabric embodying this design. A repetitive unit of the design is enclosed within the dot-dash lines.

Fig. 2 is a sectional view taken on the line II—II shown in Fig. 1.

I claim:

The ornamental design for a pile fabric, as shown and described.
